W. P. Hutchinson,

UNITED STATES PATENT OFFICE.

SAUL ROZENE, OF BRIDGEPORT, CONNECTICUT, ASSIGNOR TO CANFIELD RUBBER COMPANY, OF BRIDGEPORT, CONNECTICUT, A CORPORATION OF CONNECTICUT.

BAG AND CLOSURE THEREFOR.

1,318,411.

Specification of Letters Patent.

Patented Oct. 14, 1919.

Application filed January 20, 1919. Serial No. 272,014.

To all whom it may concern:

Be it known that I, SAUL ROZENE, a citizen of the United States, and a resident of the city of Bridgeport, county of Fairfield, and 5 State of Connecticut, have invented a new and useful Improvement in Bags and Closures Therefor, of which the following is a full, clear, and exact description.

My invention relates to improvements in 10 bags and closures for the same, and is primarily intended as an improvement in ice or hot water bags, although the bag, and especially the closure, can be used for other purposes. Ice and hot water bags especially 15 are generally made with metallic nozzles or filling parts, which are open to serious objections. From a structural point of view the nozzles are not easily applied, and they are quite likely to work loose or break away so 20 that the bag will leak around the nozzle, and when used the cold or hot metallic part is likely to come in contact with the person to whom the bag is applied, much to his discomfort. Furthermore if the bag is used 25 as an ice bag it is difficult to fill it through the ordinary nozzle. My invention is intended to overcome these difficulties and produce a simple form of bag and closure in which a relatively wide mouth of flexible 30 material, generally the same material as the rest of the bag, is used, so that in the case of ice or other material the filling is easily accomplished as the ice can be shoveled or scooped easily into the wide 35 mouth of the bag. While the mouth can be of any width, it may if desired be made substantially the full width of the bag, this rendering filling very easy. Another and important advantage of this structure 40 of the mouth portion is that when the bag is filled, the flexible mouth portion can be rolled up thus effecting a tight seal, and it can be held in the rolled or closed position by suitable fasteners as hereinafter 45 described. This form of closure as it is simple and inexpensive and effects a tight seal, can be used as a bag closure for many other purposes. The bag embodying my improvement can be made in any desired shape so 50 as to fit different parts of the body, as for instance the head or limbs, and I provide it with means for fastening the bag on the particular portion of the body desired. These and other advantages will appear

more fully from the description which follows.

Reference is to be had to the accompanying drawings forming a part of this specification, in which similar reference characters indicate corresponding parts in all the 60 views.

Figure 1 is a perspective view showing the application of the bag to the head of a patient.

Fig. 2 is a broken detail plan of one form 65 of the bag with the mouth closed.

Fig. 3 is a side elevation of the bag with the mouth portion open and extended.

Fig. 4 is a longitudinal section of the structure shown in Fig. 3.

Fig. 5 is a perspective view showing the application of another form of the bag to the arm of a patient.

Fig. 6 is a broken plan view of the form 70 of bag shown in Fig. 5, with the mouth closed.

Fig. 7 is a side elevation of the structure shown in Fig. 6.

Fig. 8 is a broken plan view of the bag shown in Figs. 6 and 7 but with the mouth 80 portion open and extended, and

Fig. 9 is a longitudinal section of the bag shown in Fig. 8.

The bag embodying my improvement can obviously be made in a great variety of 85 shapes and for many different purposes, but I have shown two forms of the bag by way of example to bring out clearly the object and use of the invention.

As shown in Figs. 1 to 4 the bag 10 is 90 especially adapted for use as a head bag, though it can be used for other purposes, and the bag 10 is of elliptical shape and has leading from the top side and connecting therewith a flexible mouth portion 11, the 95 whole being, as will be understood, of waterproof material, and the bag can be filled through this wide mouth portion. The width of the mouth portion can naturally be made as desired, but it is better to have it 100 pretty nearly as wide as the body portion of the bag, and if the bag is used for an ice bag the ice can be quickly and easily put in through this wide mouth portion. When the bag is to be sealed this mouth portion is 105 simply rolled up and an air tight and water tight seal is thereby effected. Various means can be used obviously for holding the

mouth portion rolled and prevent it from loosening up so as to spill the contents of the bag, and I have shown an approved and efficient fastening means without, however, limiting the invention to this form of fastening. As illustrated, snap fasteners are used of which one portion 12, in the instance shown the bottom portion, is fastened to the bag on one side of the mouth portion 11, 10 while the socket members 13 of the fastenings are secured to the opposite side of the mouth portion, so that when this mouth portion is rolled up as shown in the drawings, the buttons 12 can be pushed into the sockets 13 and the mouth portion secured in its closed position. It will be seen that when thus secured there is no metal to come in contact with the patient, and the sealing is easily and nicely effected.

20 In Figs. 5 to 9 I have shown another form of the bag to emphasize the fact that the bag can be made in very many different shapes. The bag here shown is easily applicable to the limbs of a patient, and here the bag 10 is simply an elongated generally rectangular bag made as before of water-proof material, and the mouth portion 11^a is the full width of the bag. This makes a very simple and efficient bag for the purpose intended, and 25 it will be seen that it can be filled with the utmost ease, and when filled the mouth portion 11^a can be rolled up as already described and fastened in the manner indicated.

Whatever the form of the bag it can be 30 readily applied and held in place on the body of a patient. For instance in Figs. 1 to 4 I have shown the head bag 10 provided with a strap 14 having a buckle 15 at one

end and a strap 16 at the other so that the fastening strap can be extended beneath the 40 chin of the wearer and secured. In Figs. 5 to 9 the straps 17 and 18 answer the same purpose and the bag can be easily bound upon the limb. In any case it will be noticed that the bag is easily filled or emptied, 45 and easily and tightly sealed, also easily applied.

As stated it will be obvious that the bag can be made in different shapes, and equally obvious that this sealing means and closure 50 can be applied to bags for other purposes. A simple and obvious way of sealing is as already described, to roll up the mouth portion of the bag; but of course it might be folded over and over upon itself which 55 amounts to the same thing as rolling and has the same effect.

I claim:—

1. A bag and closure therefor comprising a closed body portion, and a wide flexible 60 mouth portion leading from one side of the bag at an angle thereto, said mouth portion being adapted to be folded upon itself to close it, and means for holding the mouth portion closed.

2. A bag and closure comprising a closed body portion, a flexible mouth portion of nearly the full width of the bag leading from one side of the bag, said mouth portion being adapted to be doubled over upon 70 itself to close it, and fastening means for holding the mouth portion closed.

SAUL ROZENE.
